US0D1079747S

(12) **United States Design Patent** (10) Patent No.: **US D1,079,747 S**
(45) Date of Patent: ** Jun. 17, 2025

(54) **DISPLAY SCREEN OR PORTION THEREOF WITH ICON**

(71) Applicant: **Google LLC**, Mountain View, CA (US)

(72) Inventors: **Michael Timothy Jakab**, Brooklyn, NY (US); **Lisa Sue Fischer**, San Francisco, CA (US); **Maurice Kenji Clarke**, Oakland, CA (US); **Stephen Ervin**, San Francisco, CA (US); **Sabrina Curry**, Emeryville, CA (US); **Naomi Cecilia Tirronen**, Tokyo (JP); **Laura Dumitru**, London (GB); **Mattias Breitholtz**, London (GB); **Meng He**, Long Island City, NY (US); **Kristopher Hom**, San Jose, CA (US); **Eliot Hill**, London (GB); **Francis Joseph Sloan**, London (GB); **Tahai Michelle Baik**, San Francisco, CA (US); **Rossa Hsieh**, San Francisco, CA (US)

(73) Assignee: **GOOGLE LLC**, Mountain View, CA (US)

(**) Term: **15 Years**

(21) Appl. No.: **29/875,042**

(22) Filed: **Apr. 28, 2023**

(51) LOC (15) Cl. **14-04**

(52) U.S. Cl.

USPC **D14/489**; D14/492

(57) **CLAIM**

The ornamental design for a display screen or portion thereof with icon, as shown and described.

DESCRIPTION

The sole FIGURE is a front view of a display screen or portion thereof with icon, showing the new design.

The dot-dash broken lines in the FIGURE show a display screen or portion thereof and form no part of the claimed design.

1 Claim, 1 Drawing Sheet
